UNITED STATES PATENT OFFICE

STARR B. ELMORE, OF ROCKY HILL, CONNECTICUT

BURIAL VAULT

Application filed February 24, 1932. Serial No. 594,773.

This invention relates to the construction of burial vaults which are designed to be placed in graves for receiving and strongly and tightly enclosing caskets containing the deceased. Such vaults are commonly made of sand and cement, or concrete, and they comprise a metal-reinforced molded repository and a metal-reinforced molded cover so fitted together that they may be readily sealed by concrete into one solid water-proof mass of masonry.

Both the repository and cover of vaults of this character are of considerable weight, and this invention relates more particularly to the cover, the object being to so construct the cover that it may be lifted and lowered without danger of accident, such as the breaking of the concrete or the pulling out of the handles which have been previously provided for this purpose.

In carrying out this invention pockets are made in both sides of the cover near each end for the reception of jaws at the ends of the raising and lowering means, which pockets are reinforced to prevent the concrete from breaking out under the weight of the cover, and are so located that they are filled and enclosed when the cover is sealed to the receptacle.

In the accompanying drawing Fig. 1 shows a side elevation of a vault which embodies this invention with the cover sealed to the repository as in use, a portion of the sealing material being broken away to expose one of the handling pockets. Fig. 2 shows an end view of the vault. Fig. 3 is a longitudinal section of the repository and cover before they are sealed. Fig. 4 is a transverse section of the same. Fig. 5 shows, on much larger scale, the adjoining upper edge of the repository and the lower edge of the cover with the handling pockets, before sealing.

The repository 1 is formed by pouring a suitable concrete composition into a mold of the requisite length, breadth and height, in which a metal reinforcing fabric 2 has been placed. Around the upper edge of the repository is a flange 3 which on the inside is recessed to provide a shoulder 4.

The cover 5 which is arch-shaped in cross

section is formed of molded concrete with an imbedded metal reinforcing fabric 6. The rim 7 of the cover is made of such size and shape that it will rest upon the shoulder 4 around the inside of the repository with a space 8 all the way around between the rim of the cover and the top of the receptacle.

In the side walls of the cover near each end are pockets 9 which are desirably undercut as at 10 to receive the jaws of the lifting and lowering apparatus. Reinforcing bars 11 are preferably imbedded in the concrete at the tops of the pockets to prevent the concrete from being broken away by the jaws of the means which are engaged therewith for lifting and lowering the heavy cover into place.

After a casket has been placed in the vault the cover is lowered into place by suitable apparatus so that its edge will rest upon the shoulder in the repository and then the space around the edge of the cover and the top of the repository is filled with concrete, as at 12, so as to seal all of the joints and fill and conceal the pockets. The sealing concrete is applied so as to fill the space and conform to the lines of the cover and sides of the repository, and when it is set the vault is practically one solid piece of air tight and water proof masonry. If at any time it is desired to remove the cover the sealing material may be chipped away and suitable means engaged with the pockets for raising it.

The invention claimed is:

1. A burial vault comprising a reinforced concrete repository having a shoulder around the inside of its upper edge, and a reinforced concrete cover with its rim of a size and shape to rest upon the shoulder in the repository with a space between the edge of the cover and the edge of the repository, said cover having in its sides near each end pockets for receiving raising and lowering means with metallic bars embedded in the concrete at the tops of the pockets.

2. A burial vault comprising a reinforced concrete repository having a shoulder around the inside of its upper edge and a reinforced concrete cover with its rim of a size and shape to rest upon the shoulder in the repository

with a space between the edge of the cover and the edge of the repository, said cover having in its sides near each end under cut pockets the top walls of said pockets having 5 downwardly extending ribs for the engagement of the jaws of raising and lowering means.

3. A burial vault comprising a reinforced concrete repository having a shoulder around 10 the inside of its upper edge and a reinforced concrete cover with its rim of a size and shape to rest upon the shoulder in the repository with a space between the edge of the cover and the edge of the repository, said cover having 15 in its sides near each end pockets for receiving raising and lowering means, and means reinforcing said pockets.

4. A burial vault comprising a reinforced concrete repository having a shoulder around 20 the inside of its upper edge and a reinforced concrete cover with its rim of a size and shape to rest upon the shoulder in the repository with a space between the edge of the cover and the edge of the repository, said 25 cover having in its sides near each end under cut pockets for receiving raising and lowering means, metal bars reinforcing said pockets, and a concrete seal filling the space around the edge of the cover and edge of the 30 repository and concealing said pockets.

STARR B. ELMORE.

35

5. A burial vault comprising a reinforced concrete repository having a shoulder around the inside of its upper edge and a reinforced concrete cover with its rim of a size and shape to rest upon the shoulder in the repository with a space between the edge of the cover and the edge of the repository, said cover having in its sides near each end under cut pockets for receiving raising and lowering means, metal bars reinforcing said pockets, and a concrete seal filling the space around the edge of the cover and edge of the repository and concealing said pockets.

40

6. A burial vault comprising a reinforced concrete repository having a shoulder around the inside of its upper edge and a reinforced concrete cover with its rim of a size and shape to rest upon the shoulder in the repository with a space between the edge of the cover and the edge of the repository, said cover having in its sides near each end under cut pockets for receiving raising and lowering means, metal bars reinforcing said pockets, and a concrete seal filling the space around the edge of the cover and edge of the repository and concealing said pockets.

45

7. A burial vault comprising a reinforced concrete repository having a shoulder around the inside of its upper edge and a reinforced concrete cover with its rim of a size and shape to rest upon the shoulder in the repository with a space between the edge of the cover and the edge of the repository, said cover having in its sides near each end under cut pockets for receiving raising and lowering means, metal bars reinforcing said pockets, and a concrete seal filling the space around the edge of the cover and edge of the repository and concealing said pockets.

50

8. A burial vault comprising a reinforced concrete repository having a shoulder around the inside of its upper edge and a reinforced concrete cover with its rim of a size and shape to rest upon the shoulder in the repository with a space between the edge of the cover and the edge of the repository, said cover having in its sides near each end under cut pockets for receiving raising and lowering means, metal bars reinforcing said pockets, and a concrete seal filling the space around the edge of the cover and edge of the repository and concealing said pockets.

55

9. A burial vault comprising a reinforced concrete repository having a shoulder around the inside of its upper edge and a reinforced concrete cover with its rim of a size and shape to rest upon the shoulder in the repository with a space between the edge of the cover and the edge of the repository, said cover having in its sides near each end under cut pockets for receiving raising and lowering means, metal bars reinforcing said pockets, and a concrete seal filling the space around the edge of the cover and edge of the repository and concealing said pockets.

60

10. A burial vault comprising a reinforced concrete repository having a shoulder around the inside of its upper edge and a reinforced concrete cover with its rim of a size and shape to rest upon the shoulder in the repository with a space between the edge of the cover and the edge of the repository, said cover having in its sides near each end under cut pockets for receiving raising and lowering means, metal bars reinforcing said pockets, and a concrete seal filling the space around the edge of the cover and edge of the repository and concealing said pockets.
